FOOD BASTING ATTACHMENT FOR BOTTLES OR THE LIKE

Bathuel R. Posada, 3700 Dean Drive, Apt. 1207,
Ventura, Calif. 93003

Filed Aug. 20, 1968, Ser. No. 13,208

Term of patent 14 years

Int. Cl. D9—02

U.S. Cl. D9—275

FIG. 1

FIG. 2

FIGURE 1 is a perspective view of a food basting attachment for bottles or the like showing my new design, the essential features of which are shown in full lines;

The bristle tufts have been omitted from FIGURES 2, 3 and 4 for convenience of illustration.

I claim:

The ornamental design for a food basting attachment for bottles or the like, substantially as shown and described.
